UNITED STATES PATENT OFFICE.

SINGLETON SMITH, OF MILWAUKEE, WISCONSIN, ASSIGNOR TO THE WALLACE & SMITH CO., OF MILWAUKEE, WISCONSIN, A CORPORATION OF WISCONSIN.

GOLF-BAG.

1,208,031.

Specification of Letters Patent. Patented Dec. 12, 1916.

Application filed May 29, 1916. Serial No. 100,551.

To all whom it may concern:

Be it known that I, SINGLETON SMITH, a citizen of the United States, and resident of Milwaukee, in the county of Milwaukee and State of Wisconsin, have invented new and useful Improvements in Golf-Bags, of which the following is a description, reference being had to the accompanying drawings, which are a part of this specification.

10 The invention relates to golf bags.

The invention is more particularly designed to provide a golf bag which is reinforced at the portions where it is most necessary.

15 The invention is further designed to provide a golf bag in which the body portion is made of leather or fabric which is reinforced by metal strips and the bottom of which is of a strong and durable construction.

20 The invention further consists in the several features hereinafter set forth and is more particularly pointed out by claims at the conclusion hereof.

25 In the drawings:

Figure 1 is a side view of the bag; Fig. 2 is a section taken on the line 2—2 of Fig. 1; Fig. 3 is a bottom view of the bag; Fig. 4 is a sectional view taken on the line 4—4 of Fig. 2, parts being broken away; and Fig. 5 is a detail sectional view taken on the line 5—5 of Fig. 2.

30 The bag comprises an open ended container having cylindrical casing 6 and a bottom 7. The casing 6 is formed of either leather or suitable fabric, such as canvas. This casing 6 is provided with spring metal reinforcing strips or ribs 8 extending along the sides thereof, each of said ribs being 35 secured to said casing by strips 9 of leather or fabric whose edges 10 are stitched to the sides of the casing. These strips 9 and ribs 8 extend to the top of the bag where they are secured to the collar 11 surrounding the 40 top by rivets 12. A strip of leather or fabric 13 is secured to the outer side of the bag and upon which the carrying handle 14 is mounted and also the lower end of the carrying strap 15 which is secured at its upper 45 end to the top of the bag. A container 16 of any suitable construction is mounted on the side of the bag for carrying the golf balls.

50 The bottom 7 of the bag consists of a collar 17 and a plate 18 of leather or fabric,

and means for reinforcing said bottom and securing the collar and plate thereto. This means consists of a metal plate 19 having an upwardly extending annular flange 20 and rivets 20' or other suitable fastening means are passed through apertures 21 in said metal plate, through the collar 17 and the lower end of the casing to secure the parts together. The metal plate 19 is shown as being of annular form but this is for the 60 purpose of eliminating weight as it may be a full plate and in either case it furnishes a reinforce to the bottom edges of the bag where it is most needed.

65 Rivets 22 or other suitable fastening means are passed through apertures 23 in the plate 19 and the plate 18 to secure said plate 18 thereto and in the bottom of the bag. With the construction above described when the bag is dragged along the ground by the user 70 as shown in Fig. 1 it will be apparent that all the wear comes on the metal plate 19 and thus injury to the bag itself is prevented.

75 In addition to the parts of the bottom thus far described, I provide an inner reinforce 80 for the bottom consisting of a circular plate 25 of sheet metal which rests upon the plate 18 and the upper side of which is faced with a piece of leather or fabric 26 suitably secured thereto. This plate 25 with the piece 85 26 is securely held in place in the bottom of the bag in the following manner. The lower ends 27 of the metal ribs 8 are passed through slits 28 made in the sides of the casing 6 in the lower portion thereof and extend downwardly, as shown in Fig. 5, so as to engage the top of the piece 26 near the edge thereof when said inner reinforcing member is pressed down into place against the bottom plate 18. The flexible ribs 8 permit 90 said inner reinforce to be pushed down into place but when said reinforce passes below the ends of said ribs, they spring back and contact with the top of said reinforce and effectually prevent its accidental displacement.

95 The invention thus exemplifies a golf bag in which the sides and bottom are suitably reinforced to form a simple and durable construction.

100 What I claim as my invention is:

105 1. A golf bag comprising a casing of flexible material, metal reinforcing ribs secured to the outside of the casing and having their lower ends passing through the casing near

the lower end thereof, a reinforced bottom secured to the lower end of the casing, and an inner reinforcing plate disposed within the bottom and held in place by the lower 5 ends of said ribs.

2. A golf bag comprising a casing of flexible material, metal reinforcing ribs secured to the outside of the casing and having their lower ends passed through the casing near the 10 lower end thereof, a bottom member, a metal reinforcing plate secured to the outside of the casing near the lower end thereof and to

the bottom member, and an inner reinforcing plate disposed upon the bottom member and held in place by the lower ends of said 15 ribs.

3. A golf bag comprising a casing of flexible material, metal reinforcing ribs secured to said casing, a bottom member secured to the lower end of the casing, and an inner reinforcing plate disposed within the bottom and held in place by said ribs.

In testimony whereof I affix my signature.
SINGLETON SMITH.
